CLAIM

The ornamental design for an electronic expansion valve motor function and resistance indicator device, as shown and described.

DESCRIPTION

FIG. 1 is a front perspective view the electronic expansion valve motor function and resistance indicator device in accordance with our new design;

FIG. 2. is a rear perspective view of the electronic expansion valve motor function and resistance indicator device in accordance with our new design;

FIG. 3. is a right elevational view of the electronic expansion valve motor function and resistance indicator device in accordance with our new design;

FIG. 4. is a left elevational view of the electronic expansion valve motor function and resistance indicator device in accordance with our new design;

FIG. 5. is a top plan view of the electronic expansion valve motor function and resistance indicator device in accordance with our new design;

FIG. 6 is a bottom plan view of electronic expansion valve motor function and resistance indicator device in accordance with our new design;

FIG. 7 is a rear elevational view of electronic expansion valve motor function and resistance indicator device in accordance with our new design;

FIG. 8 is a front elevational view of electronic expansion valve motor function and resistance indicator device in accordance with our new design; and,

FIG. 9 is a right front perspective view of the electronic expansion valve motor function and resistance indicator device in accordance with our new design.
